United States Patent Office

Des. 185,860
Patented Aug. 11, 1959

185,860

MICROPHONE CASE OR SIMILAR ARTICLE

Richard G. Armstrong, West Springfield, Pa., and Maurice M. Palo, Conneaut, Ohio, assignors to The Astatic Corporation, Conneaut, Ohio, a corporation of Ohio

Application October 6, 1958, Serial No. 52,878

Term of patent 7 years

(Cl. D26—14)

Fig 1

We claim:

The ornamental design for a microphone case or similar article, as shown and described.
